INTELLECTUAL PROPERTY LAW, PC; Margaret Polson

CLAIM

The ornamental design for a tricycle, as shown and described.

DESCRIPTION

FIG. 1 is a front isometric view of a new design for a tricycle.

FIG. 2 is a back isometric view of FIG. 1.

FIG. 3 is a front elevation view of FIG. 1.

FIG. 4 is a back elevation view of FIG. 1.

FIG. 5 is a right side elevation view of FIG. 1.

FIG. 6 is a left side elevation view of FIG. 1.

FIG. 7 is a top plan elevation view of FIG. 1.

FIG. 8 is a bottom plan elevation view of FIG. 1.

FIG. 9 is a front isometric view of a new design for a tricycle in a folded configuration.

FIG. 10 is a back isometric view of FIG. 9.

FIG. 11 is a front elevation view of FIG. 9.

FIG. 12 is a back elevation view of FIG. 9.

FIG. 13 is a right side elevation view of FIG. 9.

FIG. 14 is a left side elevation view of FIG. 9.

FIG. 15 is a top plan elevation view of FIG. 9; and,

FIG. 16 is a bottom plan elevation view of FIG. 9.

The tricycle is shown shaded in separate tones. The surface contrast between the separate tones form no part of the claimed design. No color, color contrast, or specific surface materials are part of the claimed design.

1 Claim, 16 Drawing Sheets
